FORM TIE

Tamis C. Schenk, New York, N. Y., assignor to
Richmond Screw Anchor Co., Inc., New York,
N. Y., a corporation of New York

Application May 31, 1934, Serial No. 728,225

4 Claims. (Cl. 25—131)

This invention relates to an improvement in form ties for concrete construction, and has for its object to provide a simple form tie which will be cheap to construct, easy to use, and entirely satisfactory in service.

More particularly, the invention comprises a form tie made from a metal rod and provided with weakened points which are located within the concrete structure after the wall has been poured, the rod being then broken off at these weakened points with the portion of the rod between the weakened points remaining within the wall and covered by the concrete after the wall has been pointed.

15 The primary object of the invention is to provide means for suitably spacing the form boards and aiding in the breaking off of the form tie at the proper weakened points.

In the accompanying drawing, wherein the preferred embodiment of the invention is shown, Fig. 1 is a plan view, with parts in section, of a wall form showing one of the form ties in position; Fig. 2 is a side elevation of the structure shown in Fig. 1, after the wall has been poured; Fig. 3 is a sectional view of a part of a wall showing the broken section of the form tie remaining in the wall; and Fig. 4 is an enlarged view, in section, of a part of the form tie.

The improved form tie is adapted for use with any suitable concrete form, which may consist of longitudinally extending boards 5, re-enforced by horizontal beams 6 and uprights 7, all of which may be used in the conventional manner. The form tie 8 consists of a section of metal rod 35 provided with short, spaced cross-bars 9 welded to it. Located adjacent to the welded bars 9 are notches 10 which weaken the body of the rod and form break-off points located within the concrete structure after the wall has been poured. 40 The rod is also provided with spaced collars 11, each of which forms a fixed stop against which a washer 12 abuts, and is held by the pressure of the form boards 5. At each of its ends, the form tie is provided with an enlarged head or washer 45 13 against which a wedge 14 is employed to draw together the parts of the form. The pressure of the two wedges 14 holds the form parts in position and presses the form boards 5 against the washers 12, holding the washers firmly against the collars 11. The collars 11 are integrally formed on the rod 8 by distorting the body of the rod through the use of suitable dies. The form boards are perforated at 15 to permit the passage of the form tie, as is clearly shown in Figs. 1 and 2. 50 55 After the concrete wall structure, indicated at

16 in Figs. 2 and 3, has been poured, the projecting portions of the form tie are broken off by being engaged by a suitable tool and twisted. The breakage of the rod occurs at the weakened points 10 located within the concrete structure. 5 The bars 9 secured to the rod 8 prevent rotation or turning of the portion of the rod located within the concrete structure while the ends of the rod are being twisted to break them off. After the ends of the rod are broken off, the openings 10 17 in the wall are filled with concrete.

The washers 12 are freely movable upon the rod 8 and while they constitute a firm abutment for the form boards 5 and accurately position the form boards, they may rotate independently of 15 the form tie and consequently do not impede the twisting movement of the ends of the form tie applied to the ends of the form tie during the breaking off of these ends. The integral formation of the collars or fixed stop elements 11 on 20 the rod 8 thickens or materially increases the strength of the rod and its resistance to fracture adjacent the outer surface of the wall structure thus preventing breakage of the rod 8 at these re-enforced points and increasing the tendency of the rod to break off at the notches 10, 25 where it is desired that the breakage occur.

In use, the form tie is readily set up and as soon as the concrete is sufficiently hard, the form tie is easily broken by twisting the ends of the rod 30 to cause the breakage of the rod to take place at the notches 10. The recesses 17 in the wall are then filled.

What I claim is:

1. A form tie consisting of a rod provided with 35 spaced weakened break-off points arranged to lie within the body of the concrete structure through which the form tie extends, the rod having portions which extend outwardly from the break-off points beyond the faces of the concrete structure 40 shaped to permit them to be rotatively twisted within the concrete structure to break them off at the break-off points a pair of spaced collars integrally formed on the rod and positioned to lie adjacent to the opposite faces of the concrete structure, said collars acting to increase the thickness and strength of the rod in those portions of the rod where they are located and serving to increase the tendency of the rod to break off at the weakened points upon twisting movement of the ends of the rod. 45 50 55

2. A form tie consisting of a rod provided with spaced weakened break-off points arranged to lie within the body of the concrete structure through which the form tie extends, said rod 55

- having end portions capable of being twisted by rotative movement in the concrete structure to break them off at the break-off points a pair of spaced stops integrally formed on the rod and positioned as to lie adjacent to the opposite faces of the concrete structure, said stops acting to increase the thickness and strength of the rod in those portions of the rod where they are located and serving to increase the tendency of the rod 10 to break off at the weakened points upon twisting movement of the ends of the rod, and washers freely rotatable on the rod and abutting against the stops under pressure of the form boards.
3. A form tie consisting of a rod having weakened break-off points, the rod being provided with end portions extending from said break-off points adapted to be broken off by twisting movement about the longitudinal axis of the rod, stops on said end portions consisting of parts formed 15 by enlargement of the diameter of the body of the rod without weakening said rod, and washers adapted to be held against said stops, the end

portions of the rod being freely movable within the washers while said end portions are being twisted.

4. A form tie consisting of a rod provided with spaced, weakened break-off points arranged to lie within the body of the concrete structure through which the form tie extends, the rod having portions which extend outwardly from the break-off points to the faces of the concrete structure shaped to permit them to be rotatively twisted to 10 cause them to break off at the break-off points within the concrete structure, and movable stop elements, each of said stop elements consisting of a collar formed by enlargement of the diameter of the body of the rod without weakening 15 the rod and a washer on the rod adapted to be pressed against the collar, those portions of the rod adapted to be broken off by twisting movement being movable within the washer during such twisting movement. 20
